PNEUMATIC IMPLEMENT.

APPLICATION FILED JAN. 19, 1915.

Patented Oct. 21, 1919.

UNITED STATES PATENT OFFICE.

OLIVER O. APP, OF NEW YORK, N. Y.

PNEUMATIC IMPLEMENT.

1,319,034.

Specification of Letters Patent.

Patented Oct. 21, 1919.

Application filed January 19, 1915. Serial No. 3,016.

To all whom it may concern:

Be it known that I, OLIVER O. APP, a citizen of the United States, residing at the city of New York, in the borough of Manhattan and State of New York, have invented certain new and useful Improvements in Pneumatic Implements, of which the following is a full, clear, and exact description.

This invention relates to fluid pressure or pneumatically operated implements primarily designed for cutting rock and similar hard substances, the implement being capable for use with a tunneling machine having a rotating head carrying a plurality of the implements which are brought into contact with the rock, as a rock drill, or pneumatic hammer and in fact any fluid pressure devices of this character.

The primary object of this invention is to provide an implement which automatically starts operating when the tool carried thereby is brought into contact with and pressed against the work and will immediately stop operating before another blow can be delivered when the pressure is removed from the tool. With tunneling machines where the invention has its chief adaptation, this is of importance since the several implements carried by the rotating head operate under varying conditions and frequently one or more of the tools are not in contact with the rock while the others are operating. Under these circumstances the implements whose tools are not in contact with the rock should immediately cease operating otherwise the next blow of the hammer or piston of the instrument will drive the tool from its holder and also break or otherwise injure the parts of the implement.

Another object of the invention is to provide an implement of this character of a simple, compact construction in which the number of movable parts, including the valve mechanism is reduced to a minimum, the parts which are subjected to the strains of the blow delivered consisting of few parts of a massive construction.

Other objects and important features of the invention will be apparent from the detailed description hereinafter to follow and will be particularly pointed out in the appended claims.

In the accompanying drawings:

Figure 1 is a central longitudinal medial

section of an implement constructed in accordance with the principles of my invention;

Figs. 2, 3, 4 and 6, respectively, are sections taken on the lines 2-2, 3-3, 4-4, 6-6, respectively; and

Fig. 5 is an end view of the implement looking toward the left.

The implement casing or cylinder 1 is open at both ends and is preferably constructed of steel as are practically all of the other parts of the implement, so as to minimize the danger of the breakage, due to the vibrations and strains to which they are necessarily subjected. The open rear end of this casing is closed by a head 2 which fits into the bore of the casing, these parts being accurately machined so that they form an air-tight joint. The head 2 is provided with a flange 3, fitting against the rear annular end face of the casing against which it is maintained by a heavy set-screw 4, which is threaded into an aperture in a boss carried by a hollow casing 5. This casing or cap which has suitable exhaust openings 5' therein is threaded interiorly and is screwed down over the exterior surface of the rear end of the casing 1, the construction described maintaining the head firmly in place against the heavy pressure to which it is subjected. The interior surface of the head 85 is provided with a cylindrical recess 7, the outer walls of the recess diverging slightly as at 8, forming a chamber into which the end of the piston enters at the completion of its rearward stroke, the purpose of which will be hereinafter set forth.

Fitted into the forward end of the casing 1, is a differential piston or hammer which is constructed from a solid bar of steel and has no openings in the same, this piston constituting the striking member which delivers the blow against the tool and in one practical embodiment of the invention is about $3\frac{1}{2}$ inches in diameter at its larger end, and weighs about 25 pounds, so that it constitutes a solid massive piece which is not liable to shatter, spread or in other ways be injured by the repeated blows which it strikes. This piston is cylindrical in form and consists of the two heads 10 and 11; the head 10 which faces the rear end of the casing is of somewhat larger diameter than the other head 12 to which it is joined by a neck

piece 12 so that a shoulder 13 is provided against which the fluid pressure may act constituting a differential piston.

The casing is bored to suitable diameters 5 as at 14 and 15 so that the heads 10 and 11 may have a sliding fit therein, and three or four thousandths of an inch clearance is preferably allowed so that there will be no tendency for the piston to stick should it expand slightly, due to the heat generated by 10 the friction between the walls of the casing and the piston, or due to the concussion of the blows which the piston strikes against the tool holder. However, to avoid any 15 leakage of the fluid, the heads are provided with piston rings 16.

Mounted in the front end of the casing or cylinder 1 is a nose-piece or bushing 17, which is driven into the casing with a force 20 fit and is thereby prevented from turning, the internal diameter of the casing being slightly larger than the bore 15 to provide a shoulder 18 against which the rear end of the bushing is adapted to seat. Slidably 25 mounted in this bushing is a tool holder 19 which is preferably cylindrical in form throughout the greater portion of its length but is squared at its rear end as at 20, the squared end passing through a suitable 30 squared aperture in the rear end of the bushing or nose piece 17. This tool holder is mounted so as to freely slide within the bushing and is prevented from inadvertent displacement therefrom by a pin 21, which 35 fits into a suitable groove 22 cut in the bushing 17 and passes through openings in the casing; the tool holder having an elongated groove 24 in its lower face just above the pin, the walls of which co-operate with this 40 pin to limit the free movement of the tool holder. The ends of the pin 21 extend the outer periphery of the casing and are flush with the same and a resilient spring band 23 surrounds the casing and covers the ends 45 of the pins to prevent their inadvertent displacement. The tool holder 19 is also preferably of steel and constitutes a solid massive piece, the weight of which is approximately fifteen pounds, where a plunger or 50 piston of twenty-five pounds of weight is used, the tool holder being lighter than the plunger so that when the latter is driven against the same, there will not be the tendency for the plunger to rebound, but 55 rather for the heavier mass to drive the tool holder forward and follow it through a greater distance whereby the strength of the blow delivered is increased. The front 60 end of the tool holder is provided with a centrally disposed squared recess which is adapted to receive a tool 25, the shank of the tool being squared to fit within this squared aperture. The tool is preferably short in length so as it will not be broken 65 or shattered by the violent impact with

which it strikes against the rock or other materials to be worked upon. These parts, namely, the tool, tool holder and piston, are alone subjected to the severe strains and stresses occasioned by the driving of the 70 piston forwardly against the tool holder with such severe blows as to cause the shattering of the rock and since they are all of steel and in each instance constitute a single solid massive piece, which are not liable to 75 be broken, but will readily withstand any tendency to shatter or spread.

The tool holder extends beyond the front end of the casing and is provided with an annular flange 26 which is provided with an annular groove 27 therein which is adapted to receive one portion of a spring-resilient retaining clamp 28 which also engages notches 29 in the square corners of the tool for retaining the latter against inadvertent displacement from the tool holder due to the vibration of the implement when 85 in operation.

Between the walls 14 and 15 of the casing and neck 12 of the piston which is of slightly 90 smaller diameter than the head 11, there is formed an annular chamber or space *a* which is bounded at its ends by the shoulder 13 which connects the neck with the large head 10 of the piston and at the other end by 95 a shoulder 12' which connects the neck with the small head 11 of the piston.

Referring now to the manner in which the implement is pneumatically actuated, as before stated, the differential piston hammer is provided with a shoulder 13, which, together with a shoulder 12', formed by the junction of the neck 12 of the piston with its head 11, and the walls of the cylinder, forms a chamber *a* to which fluid pressure 100 is admitted through ports 30 and 31, leading through the top part of the casing. The port 31, as shown, is preferably inclined and converges toward the port 30 and the cylinder. Adjacent the inner ends of these ports, 110 the bore of the cylinder has a groove or annular section of slightly enlarged diameter, as at *b*, so that when the piston is in its extreme forward movement and the shoulder 13 rests against the shoulder 12' which 115 connects the bores 14 and 15 of the cylinder, fluid pressure will still be freely admitted to exert its pressure against the shoulder 13.

The admission of the fluid pressure through the ports 30 and 31 is controlled by 120 the valve mechanism which will now be described.

The curved peripheral surface of the casing above the ports 30 and 31 is cut away as at 32, to provide a flat seat upon which the 125 valve chest 33 is mounted and secured in place by the bolts 34 to provide a substantially air tight connection between the chest and casing. The main reservoir chamber of the valve chest is shown at *c*, and positioned 130

- below this chamber is a slide valve 35 which is fitted into a suitable recess formed in the lower face of the valve chest so that it may rest directly upon the seat 32. Ports 36 and 5 37 are provided in this slide valve which are adapted to register with the ports 30 and 31, respectively, when the valve is in open position, a plurality of ports being preferably provided so that the area of admission 10 for the fluid pressure to the cylinder may be increased without increasing the stroke of the slide valve. The fluid pressure is admitted to the chamber *c* of the valve chest through the pipe 38, which is threaded into 15 a sleeve or boss 39 carried by the valve chest, it being understood that the pipe 38 conducts the fluid pressure to the implement from any suitable source. Leading rearwardly from the chamber *c* is a conduit 40 which is 20 enlarged at its rear end as at 41 and extends downwardly so that the rear end of the slide valve is exposed to the action of the fluid pressure. The opposite or front end of the valve is open to the atmosphere, the passage 25 42 being provided through the front face of the valve chest into which one end of a loosely fitting rod 43 is adapted to extend, so that it presses against the end of the slide valve. The rod 43 extends forwardly to the 30 extreme forward end of the casing and lies in a groove 44 in the casing. The front end of this rod abuts against a lug 45, which forms an integral part of the tool-holder. As the rod 43 fits loosely into the opening 41 in 35 the front end of the valve chest, the same is open to the atmosphere, and in order to prevent the leakage of the fluid pressure between the contacting faces of the valve and valve chest along the line 46, a flap valve of 40 leather or other construction is fitted into the slide valve. This flap valve may comprise a flap of leather 47, which is inserted into a suitable transverse groove in the top surface of the valve. It has been found impossible, 45 however, in the construction of the implement shown, to make the joint entirely airtight, and this fact has been taken advantage of in lubricating the tool holder, which is accomplished by providing the duct 48. As 50 is common in fluid pressure tools or implements of this character, the lubricating oil is fed in mixed with the compressed air, so that when the same escapes between the surfaces designated 46, the oil will follow the 55 groove in the casing until it reaches the duct, which will carry it downwardly to the face of the tool-holder so that the same will slide without undue friction in the bushing 17. 60 The fluid pressure is admitted to the rear end of the piston by means of the longitudinally disposed inlet conduits 50, which, as is clear from Fig. 2 of the drawing, are drilled in the side walls of the casing, and are ten in 65 number, five being arranged each side, al- though a greater or less number of conduits may be provided, the essential point being that sufficient conduit area be provided so that the fluid pressure may pass freely to the rear end of the piston at the proper time in 70 the operation of the same. These conduits 50 lead into the bore 14 of the casing through openings 51 at their front ends and at their rear ends by the openings 52, the casing being of enlarged diameter adjacent the openings 52 to provide a beveled surface 53 so that when the head of the piston reaches the ports 52, the fluid pressure will not be cut off but will permit the fluid pressure to enter the compression cup chamber 7. 75 The exhaust ports for the casing are, in the preferred embodiment of my invention, formed by providing longitudinal grooves in the exterior surface of the casing, which grooves are surrounded by a metallic shell 54 80 which is fitted over the casing to form the exhaust conduits. The casing is preferably of reduced diameter so that the exterior surface of the shell and the front end of the casing will be flush; the front end of this shell fitting against a shoulder 55, while the rear end fits into a suitable groove 56 formed in the cap 5, which rigidly maintains the same in place. These exhaust conduits are in several sets, one set 57 being 85 four in number and arranged in the lower portion of the casing, which conduits lead into the cylinder at a point 58 adjacent the end of the tool-holder and also through 90 openings 59 which are arranged to the rear of the piston when the same is in its forward position. The conduits 57 extend to the extreme rear of the casing and also through openings 60 formed in the flange 95 of the cap 3, so that the air may be freely exhausted through the exhaust opening 5' 100 in the cap 5. Another set of exhaust conduits 61 four in number, are arranged on the top of the casing at the rear end thereof, which conduits have openings 62 leading 105 into the cylinder at a point in radial alignment with the openings 59, and similar to the other exhaust conduits described, pass through suitable openings in the flange of the cap 3, so that they may be exhausted 110 through the openings 5'. For the rear end of the cylinder 8 exhaust conduits are therefore provided, but for the forward end of the cylinder, since the valve mechanism prevents the conduit from being extended forwardly, and since the inlet conduits 50 prevent other conduits from being formed in the side of the casing and extended to the rear end of the casing, it is necessary to provide the conduits 63 which preferably do not 115 open to the atmosphere at their rear ends. These conduits are four in number, and are shown in cross section in Fig. 4, and open into the cylinder as at 64 extending rearwardly of the cylinder to a point approxi- 120 125 130

mately opposite the ports 30 and 31; these conduits will be hereinafter referred to in the description of the operation of the implement.

5 Assuming that the line pressure is being conducted to the implement through the pipe connection 38, and that the tool is removed from work, the fluid pressure behind the slide valve will immediately throw it to 10 closed position and the tool will remain inactive. If, however, the tool 25 is forced against the work through the instrumentality of the rod 43 the valve 35 will be pressed or moved toward its open position corresponding to the pressure which is exerted by 15 the tool upon the work. The registering of the ports in the slide valve with the ports 30 and 31 will admit fluid pressure to the chamber *a*, and since the rear of the piston 20 is open to atmosphere through the exhaust conduits 57 and 61, the fluid pressure exerted against the shoulder 13 will tend to force the piston rearwardly in the cylinder at a considerable speed. As the piston moves 25 to its rearmost position the shoulder 13 passes beyond the openings 51 of the inlet conduits 50 so that the fluid pressure is admitted behind the piston and as the momentum of this piston carries it rearward, a part 30 of the fluid pressure will be trapped within the compression cup 7 and compressed to an extent greater than line pressure. As for example, the speed of the piston may be such that its momentum will be sufficient to permit 35 it to compress the fluid pressure within the trap chamber 7 to $\frac{1}{3}$ of its volume, there will be a corresponding increase of pressure, and if a line pressure of 80 lbs. were used, this would be 640 lbs., which would be acting 40 against each square inch of the rear face of the hammer or piston to again move it forward.

The forward movement of the piston is, therefore, initially received by the compressed air within the chamber 7, and after the end of the piston has passed out of this chamber the fluid pressure will be admitted to the cylinder behind the piston until the shoulder 13 again covers the openings 51 of 45 the inlet conduits 50, after which the piston will move forward under the expansive action of the fluid pressure until the exhaust ports 59 and 62 are opened when the piston will continue its forward movement under 50 its own momentum until it strikes the squared end 20 of the tool-holder, which blow will be communicated to the tool 25 which is in contact with the work and cause the tool to impinge against the rock or other 55 hard surface to be cut to shatter the same. During this forward movement of the piston, as in all movements of the piston, the chamber to the front of the head 11 is open to atmosphere through the exhaust conduits 60 58, but in order to prevent any unnecessary

retardation of the piston on its forward stroke the additional exhaust conduits 63 are provided, which, as described, do not lead to the atmosphere, but merely serve as an auxiliary space in which part of the air 70 to the front of the head 11 which can escape through the conduits 57 may be compressed on the forward stroke of the same. This has been found a desirable construction, since the exhaust ports 57 which open to the atmosphere are not of sufficient area to permit the desired rapid reciprocation of the piston within the cylinder. If desired, the conduit 63 could also lead to the atmosphere, but this construction would weaken the casing and I have found this unnecessary when the additional compressing space is supplied. 75

During this forward movement of the piston the fluid pressure which is admitted to the chamber is forced back into the valve 80 chest by the forward movement of the shoulder 13, but the comparative areas of the shoulder 13 and the rear face of the piston are such that this slight retardation of the piston in its forward movement does not 85 materially affect its speed and the force of the blow delivered.

Just prior to the piston striking the tool-holder the chamber to the rear of the piston is thrown to exhaust by means of the exhaust 90 conduits 57 and 61 as has been referred to, and after the blow is delivered the piston again moves rearwardly under the pressure exerted upon the shoulder 13. The actuation of the piston while in operation is very 95 rapid and in the actual embodiment of the machine as many as 1000 blows per minute have been struck which, due to the weight of the piston, will cause the tool to impinge against the rock with such violent force that 100 large pieces of the rock are broken from the mass which it is desired to cut, which operation will be continuous as long as the slide valve remains open. If, however, the tool is not pressed against the work, the unbalanced slide valve will then immediately 105 move to closed position, and through the instrumentality of the rod 43 which bears against a portion of the tool holder, force the same forwardly in the cylinder until the 110 walls of the groove 24 engage the pin 21. This movement of the slide valve is practically instantaneous, since in the practical embodiment of my invention which I have constructed, the area of the rear face of the 115 slide valve is at least of a square inch area, and since the line pressure is from 75 to 95 lbs., this whole pressure is exerted against the slide valve to throw it forwardly. It is also clear that by providing a plurality 120 of ports in the casing and slide valve to completely close these ports 31, the slide valve does not have to move through an extended distance. This action, as stated, is practically instantaneous and due to the construc- 125 130

tion of the differential piston and air ports and arrangement of inlet and exhaust ports shown, the piston will be stopped before it is moved to deliver a blow against the tool holder, irrespective of its position at the instant the tool is removed from the work. If, for example, the piston has just delivered its blow and is in the position shown in Fig. 1 when the slide valve is closed, the fluid 5 pressure will act expansively against the shoulder 13 and move the piston rearwardly until the exhaust openings 57 and 62 are closed. After closing the exhaust openings 10 the air to the rear of the head 10 will be compressed until the pressure exerted upon 15 the shoulder 13 is equal to the same and the piston will cease moving. Again, assuming that the piston is in its rearmost position and has just started forwardly on its stroke when 20 the valve is closed, here the pressure of the compressed air in the trapped chamber 7 will cause the piston to move forwardly at a relatively great speed. This speed will be increased after the piston leaves the chamber 25 as the fluid pressure admitted to the chamber through the openings 52 is permitted to act expansively, but during the forward driving of the piston, since the slide valve is closed, the shoulder 13 will compress 30 the air in the chamber *a*, which, in the normal operation of the valve, is permitted to back into the line through the open ports 30 and 31, and the forward movement of the piston will continue until the air within the 35 chamber *a*, that is, the air which is trapped by the closing of the slide valve, is compressed until the pressure which it exerts upon the shoulder 13 equals the pressure of the fluid against the rear face of the head 40 10, which, as has been stated, is acting expansively. The piston will, therefore, be stopped on its forward movement before a blow can be delivered against the tool-holder to drive the same from the cylinder and 45 perhaps break the pin 21 or mutilate the tool-holder, due to the shock which would be occasioned by the impact of the walls of the groove 24 against the pin 21. In the same manner, if the piston is in any of its 50 intermediate positions and is moving forwardly or rearwardly, it will be stopped before the blow can be delivered. And I find that even where the implement is operated so that its piston will deliver from 1000 55 to 1200 blows a minute, in every instance, just as soon as a tool is removed from the work the same immediately stops actuating before another blow can be delivered by the piston against the tool and tool-holder. It 60 is for this reason that the form of implement shown is especially adapted for use with tunneling machines, since in this adaptation it is impossible to manually control any of the tools which are placed upon a rotating 65 head, and the actuation of the same must be

taken care of automatically, so that they will only operate when they are in firm contact with the rock or other substance to be cut.

The desirable results obtained by this form of implement, it is believed, are partly 70 due to the simplified form of the valve mechanism, wherein the use of any distributing valves or other auxiliary valves is entirely dispensed with and the control is directly from the main valve. 75

Another important feature of the invention may be grasped by considering the pressure exerted by the fluid against the unbalanced slide valve, as it is obvious that this may be controlled within the widest possible limits, since if it is desired to obtain an implement which will actuate after a certain pressure is exerted upon the point of the tool, it is only necessary to design the slide valve so that the area which is exposed to the fluid pressure will correspond thereto; as for example, if in heavy operations where the line pressure is 80 lbs. and it is desirable that the tool should only operate when it is pressed with considerable 80 pressure against the work, the slide valve may be so designed that it exposes an area of $1\frac{1}{4}$ sq. in. to the fluid pressure, in which instance it will take 100 lbs. pressure or more upon the point of the tool to move 85 the valve to fully open position. 90

Another advantage of the form of valve mechanism disclosed is that if the tool is only pressed lightly against the work the result will be a correspondingly light blow, 100 as it is obvious that upon a slight movement of the tool-holder and rod 43 the slide valve will only be partially opened and the amount of fluid pressure admitted to the chamber *a* will not be sufficient to permit the piston to 105 strike a blow of full strength, as the fluid pressure will act expansively for the greater part of the stroke of the piston. 110

I claim:

1. In a fluid pressure operated implement, 110 a cylinder, a piston therein having an annular shoulder, said piston and cylinder forming an annular chamber one wall of which is formed by said annular shoulder, a port in said cylinder leading to said annular chamber, a valve for controlling said port said valve being normally biased to its closed position, and means operated by being pressed against the work for opening said valve. 115

2. In a fluid pressure operated implement, 120 a cylinder, a piston therein having an annular shoulder, said piston and cylinder forming an annular chamber one wall of which is formed by said annular shoulder, a port in said cylinder leading to said annular chamber, a valve for controlling said port said valve being normally biased to its closed position, a movable tool carried 125 by said cylinder, and a connection from said 130

movable tool to said valve whereby when said tool is pressed against the work said valve is brought to its open position.

3. In a pneumatically operated implement, 5 a cylinder, a differential piston therein having an annular shoulder, said cylinder and piston forming an annular chamber one wall of which is formed by the annular shoulder, a main inlet port leading to said annular 10 chamber, a valve controlling said port, and fluid-pressure means for urging said valve to its closed position, and a connection to said valve for opening said valve when pressure is applied to said connection.

15 4. In a pneumatically operated implement, a cylinder, a differential piston therein having an annular shoulder, said cylinder and piston forming an annular chamber, one wall of which is formed by the annular shoulder, 20 a main inlet port leading to said annular chamber, a valve controlling said port, a tool movably mounted in said cylinder, means for urging said valve to its closed position and said tool to its outward position, 25 said means including an interconnec-

tion between said tool and valve whereby the movement of one of these parts controls the movement of the other.

5. In a pneumatically operated implement, 30 a cylinder, a differential piston therein having an annular shoulder, said cylinder and piston forming an annular chamber one wall of which is formed by the wall of the shoulder, a main inlet port leading into said chamber, a valve for controlling said port having unequal fluid pressure acting against its opposed faces and continually urging said valve to its closed position, and a connection between said valve and tool permitting one to actuate the other, the unbalanced pressure acting against said valve being of sufficient force to move said tool to its outward position. 35

In witness whereof I subscribe my signature, in the presence of two witnesses.
